UNITED STATES PATENT OFFICE

164,225

BENCH OR SIMILAR ARTICLE

Thomas M. Dunham, Aurora, Ill., assignor to
Aurora Equipment Company, Aurora, Ill., a cor-
poration of Illinois

Application March 12, 1949, Serial No. 1,370

Term of patent 14 years

(Cl. D33—14)

To all whom it may concern:

Be it known that I, Thomas M. Dunham, a citizen of the United States, and a resident of the city of Aurora, in the county of Kane, and State of Illinois, have invented a new, original, and ornamental Design for a Bench or Similar Article, of which the following is a specification, reference being had to the accompanying drawing forming a part thereof.

In the drawing:

The single figure is a perspective view of my novel design for a bench.

I claim:

The ornamental design for a bench or similar article, as shown.

THOMAS M. DUNHAM.
